CLAIM

The ornamental design for a wheel bearing, as shown and described.

DESCRIPTION

FIG. 1 is a front perspective view of the present invention.

FIG. 2 is a front elevation view of FIG. 1.

FIG. 3 is rear side elevation view of FIG. 1.

FIG. 4 is a bottom plan view of FIG. 1.

FIG. 5 is a top plan view of FIG. 1.

FIG. 6 is a left side elevation view of FIG. 1.

FIG. 7 is a right side elevation view of FIG. 1.

FIG. 8 illustrates a reference rear view of the wheel bearing for a wheel according to the embodiment.

FIG. 9 illustrates a combined sectional view taken along line A-B-C in FIG. 8 of the wheel bearing according to the embodiment; and,

FIG. 10 illustrates a combined sectional view taken along line A-B-C in FIG. 8 of the wheel bearing according to the embodiment in an assembled state with a wheel.

A wheel bearing for a wheel supports a wheel of vehicle in a rotatable manner. In the drawings, the broken lines depict unclaimed environmental subject matter and form no part of the claim. No claim is made to portions that are not shown. The inner portions are not claimed and are provided for illustrative purposes in FIGS. 9 and 10. The surface is lined for contour only.
